UNITED STATES PATENT OFFICE.

GEORGE H. SACKETT, OF BROOKLYN, NEW YORK.

FOUNTAIN-PEN.

SPECIFICATION forming part of Letters Patent No. 349,752, dated September 28, 1886.

Application filed November 28, 1884. Serial No. 148,932. (No model.)

To all whom it may concern:

Be it known that I, GEORGE H. SACKETT, of Brooklyn, in the county of Kings and State of New York, have invented an Improvement 5 in Fountain-Pens, of which the following is a specification.

The object of this invention is to provide a fountain-pen of cheap and simple construction, easily supplied with ink, not liable to 10 get out of order, capable of cleanly and convenient use, capable of employment with ordinary pens, and readily permitting one pen to be replaced by another, when desired.

My invention comprises certain novel means 15 whereby said objects are effectually secured.

Figure 1 is a side view and longitudinal sectional view illustrating my said invention. Fig. 2 is a transverse sectional view taken in the line *y y* of Fig. 1. Fig. 3 is a side view and 20 partial longitudinal sectional view showing a modification of my said invention. Fig. 4 is a side view of certain parts, of which Fig. 5 is also a side view, but taken in a plane at right angles to Fig. 4. Fig. 6 is a transverse sectional view taken in the line *u u* of Figs. 4 25 and 5.

A is the reservoir or hollow holder of the pen of the usual cylindrical form, closed at its upper end, open at its lower end, except as 30 hereinafter explained.

B is the plate or diaphragm inserted in the lower end of the reservoir A, and retained in place either by friction or by any other suitable means. In this diaphragm is an opening, 35 *a*, through which ink passes to the pen when the latter is in use, and through which air may pass to the reservoir to replace the ink as exhausted therefrom. When desired, one opening, *a*, may be arranged to feed ink to the pen, and in this opening the pen is inserted 40 and retained, as indicated in the drawings; and another opening provided in said diaphragm to permit the passage of air, as shown at *b* in Figs. 1 and 2.

C is the pen, which is inserted and held in the opening *a*, formed in the diaphragm B.

D is a tongue or lip, preferably formed integrally or in one piece with the diaphragm B, but which, when desired, may be formed separately and affixed thereto by any suitable means. This lip D extends downward substantially parallel with the pen, the lip being

either at the outer or inner side of the pen, as preferred. The office of the said lip is to assist in feeding the ink regularly from the reservoir toward the point of the pen, the ink flowing through the passage between the pen and the lip. 55

E is what I term an "expansion-chamber"—that is to say, a chamber which receives any 60 excess of ink, which, as may sometimes occur, may be forced out through the opening *a* by an expansion of air above the ink within the reservoir from an increased temperature of the air. This expansion-chamber may, however, be dispensed with when desired. 65

F is a feeding-stem which is extended from the diaphragm upward into the reservoir to facilitate the descent of the ink downward therein to supply the pen, and also, when the 70 implement is inverted, to facilitate the inward flow of the ink when the reservoir is filled. This feeding-stem may be made single, as indicated in Figs. 1 and 4, or it may be made double the whole or any portion of its length, 75 as indicated in Fig. 5, the space between constituting substantially a groove.

The most approved construction and arrangement of the parts is that represented in Figs. 3, 4, 5, and 6. In this the diaphragm 80 carries the pen, the lip, and the feeding-stem, and is capable of easy attachment to and detachment from the reservoir for filling or changing the pen, and is preferably held in place in the lower or open end of the reservoir 85 by being snugly pressed therein, or, in other words, held by friction. With the construction as represented in said figures the diaphragm is to be inserted in place, as represented in Fig. 3, so that the expansion-chamber E 90 is constituted by the diaphragm as the top thereof, and by the lower portion of the walls of the reservoir as the sides or walls of said chamber.

Having on March 20, 1886, filed an application for Letters Patent claiming certain improvements in fountain-pens, which said application has since been allowed, I hereby, for the purposes of this my present application, disclaim all features which are claimed in said application of March 20, 1886. 95

What I claim herein as my invention is—

1. The combination, in a fountain-pen, of the tubular reservoir A, tightly closed at its upper

end, and the diaphragm provided with the lip and pen, said diaphragm having a passage for ink from the interior to the capillary channel between the lip and pen, and an opening, *a*, for the admission of air to the lower end of the reservoir, whereby an air-tube may be dispensed with, substantially as and for the purpose herein set forth.

2. The combination, in a fountain pen, of a diaphragm constructed with a suitable opening to receive and retain a writing pen, and with an air passage or opening, *a*, a lip, *D*, at-

tached to said diaphragm and arranged to lie substantially parallel to said writing pen, and a feeding stem, also attached to said diaphragm, the whole constructed and arranged for insertion in and removal from the reservoir of a fountain pen, all substantially as and for the purpose herein set forth. 15

GEORGE H. SACKETT.
